RUPERT EVAN HOWARD CARPENTER, OF PURLEY, ENGLAND

ELECTROMAGNETIC DEVICE

Application filed April 4, 1929, Serial No. 352,494, and in Great Britain April 25, 1928.

This invention relates to electromagnetic devices, the operation of which depends upon the action of a fluctuating magnetic flux linking with the armature of the device. The invention has special reference to the magnetic structures employed in such devices; it is applicable to instruments or machines wherein mechanical motion either rotary or oscillating, is produced in a member corresponding to currents or potentials applied to the machine or instrument, such as is necessary, for example, on the one hand in electromagnetic motors, or on the other hand in electromagnetic relays, and the driving units employed in sound reproducing instruments. However, the invention is also applicable to machines depending upon the converse action, namely, the production of an electro-motive force dependent upon the driving of a moving member as, for example, is the case in magneto-electric machines employed in ignition for internal combustion engines and other electric generators.

There are a number of points which require careful consideration in the design of the magnetic circuit of an efficient relay or similar electromagnetic device. The part of the magnetic circuit acted upon by a reversals coil, which may be called the reversals circuit, should have minimum reluctance, and the total reluctance of this circuit should only be slightly greater than that of the air gaps and the core carrying the reversals winding, whilst as much as possible of the flux change produced by the current in the reversals coil should operate on the armature. Again the hysteresis and eddy current losses in that reversals circuit should be as small as possible, and should be limited substantially to the losses in the core carrying the reversals winding.

In order to obtain these two conditions, it is necessary to arrange for the steady polarizing flux not to pass through the core carrying the reversals winding, and to make those portions of magnetic material traversed by both the fluctuating flux and the steady polarizing flux of large cross-section for two reasons: First, all known ferromagnetic material has the property that the presence of a

steady flux greatly reduces the incremental permeability of the material, and secondly any desired intensity of polarizing flux may be employed without any limitation which would otherwise be imposed by the cross-section of the core carrying the reversals winding. The next point is that the armature should have a minimum moment of inertia, and as a secondary matter, should be mounted in such a way that bearings or pivots, if they are used, shall be readily accessible. One pair of air gaps should be employed since the use of two pairs, particularly if the axis of oscillation of the armature lies between them, increases considerably the accuracy needed in manufacture, and in any case for a given change of reluctance for unit movement of the armature, air gaps of only one-half the length must be employed when two pairs of a given cross-sectional area are arranged in series in the reversals circuit. A bias adjustment should be provided gradual in its action but not dependent upon great mechanical nicety of manufacture. Further, it is advantageous to employ only one spool for the reversals winding surrounding a stationary core and easily replaceable if it should be burned out.

It is the principal object of the present invention to provide a magnetic circuit which lends itself to a design in which all these advantages can be combined in a way which has not been possible previously, and at the same time to keep the manufacturing cost very low.

According to the present invention, the magnetic structure of a device of the above kind consists of a portion having a magnetic circuit of low reluctance to carry the fluctuating flux, and a portion of relatively large reluctance in which the steady flux flows in two parallel paths, the reluctance of the latter portion is sufficient to avoid serious shunting with respect to the fluctuating flux of the part of the magnetic circuit of low reluctance in which the effective air gap is disposed. Thus, steady fluxes preferably equal in value, flow in the two parts of the high reluctance part of the magnetic structure and are only subject to small variations. Thus,

when the invention is applied to an electro-magnetic relay the vibratory armature is located in a gap between the pole faces of two limbs, preferably of relatively large cross-section, and the circuit for the fluctuating flux is completed by a bridge-piece which carries the coil of the instrument, and may be of smaller cross-section than the said limbs, because this bridge-piece does not have to carry the steady or polarizing flux. The divided part of the magnetic structure in which the latter flows may consist of a pair of permanent magnets, the like poles of which are connected to a central limb of the magnetic structure on which the vibratory armature is supported.

This construction enables the bridge-piece to be formed of laminated material, and to be readily removed and replaced by a piece carrying a coil of different resistance. Moreover, the construction allows of very convenient forms of biassing. Biassing may be effected by employing a wandering or adjustable magnet or magnetic member which can be set into a position so as to shunt, or in the case of a magnet, either to shunt or assist one or other of the two permanent magnets of the instrument until any steady flux in the bridge-piece carrying the coil is neutralized. In order to render the invention clear, and to enable same to be carried into effect without difficulty, a form of telegraph relay and a form of small rotary motor constructed in accordance with the invention, will be described in greater detail with reference to the accompanying drawings, wherein:

Figure 1 is a rear elevation of a relay with the biassing magnet shown broken away;

Figure 2 is an elevation seen from the left of Figure 1; while

Figure 3 is a plan with the coil and the base removed;

Figure 4 is an enlarged cross-section showing the method of clamping the butts of the relay in their adjusted positions,

Figure 5 is an elementary diagram of the magnetic circuit employed; and

Figure 6 is a diagrammatic elevation of a small rotary motor constructed in accordance with the invention.

Referring first to Figures 1 and 2, the magnetic structure comprises a lower horizontal limb 1 connected near its outer end by two permanent magnets 2, 3 to limbs 4, 5, which form the part of the low reluctance magnetic circuit through which the steady flux passes. The magnets 2, 3 are made of cobalt steel or similar material of high retentivity and coercivity. Like poles of the two magnets are connected to the horizontal limb 1, and mounted on the central part of the limb 1 is the central member 6 of the system, so that flux from the magnets 2 and 3 pass in parallel through the member 6 in the same direction.

The armature 7 of the relay carrying the

tongue 8 is shown pivoted to the central limb 6, it being carried by short blade springs 9 clamped in non-magnetic brackets 10, so that the downward pull on the armature 7 places the springs 9 in tension. The armature 7 could, however, be carried on a knife edged pivot on the limb 6, and in the case of a driving element, for example, for a loud-speaking telephone receiver, the member 6 could be pivoted at its lower end and itself form the vibratory reed. The butts 11, 12 of the relay are adjustably carried in pillars 13, 14 which are carried on the limbs 4, 5 and insulated therefrom, for example, by mica washers.

The method of clamping the butts is illustrated in greater detail in Figure 4, which shows the pillar 13 in vertical section. The vertical bore through the centre of the pillar 13 is tapped and a horizontal hole 15 is drilled at right angles to it. The screwed stud 16 is screwed into the lower part of the bore and serves for fixing the pillar 13 to the limb 4.

The stem 17 of the butt 11 is passed through the hole 15 into which it is screwed by a fine thread, and after final adjustment is clamped by dropping a small hardwood plug 18 on to it in the bore in the pillar 13 and clamping the plug down finally by a screw 19, this avoids any difficulty in screw-threading the pillars 13, 14, and avoids the use of split pillars and complicated clamping devices. The limbs 4, 5 are L-shaped in plan, as seen in Figure 3, and their outer ends are connected by the laminated bridge-piece 20. The latter is shown let into notches in the members 4 and retained in position by clamping plates 21 which can be readily removed to allow the bridge-piece 20 to be taken away and replaced by another bridge-piece with a coil of different resistance. The whole of the reversals circuit comprising the limbs 4, 5 and the bridge-piece 20 can be made laminated, in which case alternate plates of two

different shapes are employed so as to provide lap joints and not butt joints in order to reduce the total reluctance. The construction then is similar to the construction of small transformer cores, the plates being clamped together, for example, by screws and clamping plates. The coil 22 is carried on the bridge-piece 20, the connecting wires for receiving the incoming signalling currents being shown at 23. At 24 are the connecting wires from the tongue 8 and the butts 11, 12 of the relay; the connecting wires are taken to appropriate terminals such as 25, 26.

It will be seen that the two magnets 2, 3 with the central limb 6, and the lower limb 1 form two similar halves of a structure external to the magnetic circuit carrying the varying flux. These two similar and equal halves are of relatively high reluctance. Air gaps, or saturated portions of reduced area

may be inserted in the divided branches to increase the reluctance particularly when electromagnets are employed for polarizing.

The bridge-piece 20 carrying the reversals 5 coil 22 is shown of smaller cross-section than the members 4, 5 forming the elongated pole-pieces. This is a convenience as regards the design of the coil 22, but it does not interfere with obtaining low reluctance over the complete magnetic circuit for the varying flux, since among other things the bridge-piece 20 forming the core of the coil 22 does not carry the polarizing flux, and it is known that the permeability of a limb of a magnetic structure is in general reduced by the presence of an appreciable steady magnetization. By means of this construction not only is the part of the magnetic structure forming the path for the steady flux external to the circuit for the varying flux divided into two independent portions in which equal fluxes flow which are maintained substantially constant under all conditions, but those two halves of the external part of the magnetic structure are themselves of relatively high reluctance and therefore do not form any magnetic circuit substantially shunting with respect to the reversing flux the part of the local circuit which contains the air gap in which the vibratory member operates.

Any flux which might possibly be shunted by these external members from the limbs of the local circuit containing the air gap would, of course, be direct waste, and if there is any substantial waste in this way, the performance of the relay, of course, would be adversely affected. Moreover, the vibrating tongue can be pivoted most conveniently to the limb 6 of the external part of the magnetic structure as by the spring connection 9, but the use of a spring may be avoided in that the tongue can turn on a knife edge on that limb. It may be pointed out, however, that the reluctance of the joint between the tongue 7 and the limb 6 has to be overcome by the polarizing magnets 2, 3, and not by the reversals winding 22, so that the sensitivity of the relay does not suffer.

The construction illustrated allows of very convenient forms of biassing. If, in the symmetrical construction illustrated there is a bias on the armature 7, it indicates that there is a steady flux flowing through the bridge-piece 20, and that that steady flux is most probably due to a steady current component in the coil 22, as for example, an earth current. In order to correct this a bar magnet 27 is provided pivoted to the lower part of the limb 6 at 28 and connected to a coiled tension spring 29 anchored to the base of the instrument at 30 so as to tend to draw over the magnet 27 to the right, as seen in Figure 1. This, however, is prevented by

the engagement between the point of an ad-

justing screw 31, and the side of the magnet 27 below the pivot 28.

Thus, if the screw 31 is screwed back the spring 29 is allowed to draw over the magnet 27 towards the right in Figure 1, whereas, if the screw 31 is screwed forward its pointed end acts as a cam, turning the top of the magnet 27 towards the left in Figure 1. Thus, the magnet 27 can be turned into such a position that it assists either one or other of the permanent magnets 2, 3 until the steady flux in the bridge-piece 20 is neutralized.

The method of operation of the structure as described will be readily understood, especially by reference to Figure 5, by considering the armature in the mid-position initially. Then the equal steady fluxes from the two permanent magnets 2, 3 will pass directly through the limbs 4, 5 into the armature 7 and down the central limb 6. When current flows in the reversing coil 22 it sets up a magneto-motive force in the bridge piece 20, encouraging some of the flux from the magnet 2 or the magnet 3 depending upon instantaneous direction of flow of the current, to pass through the bridge-piece 20 in preference to passing direct through the respective limb 4 or 5 and thus to enter the armature 7 on the opposite side. By this reason there is a preponderance of flux entering the armature 7 on one side, the armature 7 being attracted on to that side and carrying the tongue 8 into contact with the butt 11 or 12 on that side.

In Figure 6 a similar motor is illustrated which is, in effect, a synchronous motor and can be used, for example, as a phonic motor for telegraphy purposes. The armature 7, in this case is a bundle of laminations with an odd number of teeth. The permanent magnets 2 and 3 are of the shape shown, and the limb 6 is reduced here to a common pole shoe. The limbs 4 and 5 each have pole-pieces coacting with the armature 7 as before, and the bridge-piece 20 is encircled by a coil 22. The whole is clamped between two non-magnetic plates 32, shown broken away, which also carry the bearings for the spindle 33 of the armature 7. It will be seen that on supplying an alternating current to the coil 22, alternately a larger flux enters the armature 7 from the limb 4 than from the limb, 5, and vice versa. It may be assumed that in the position shown the tooth 34 has been attracted to the limb 4, but in the next cycle the flux through the limb 5 preponderates and draws the tooth 35 to its pole face, and in this way continues rotating of the armature 7 is maintained, the armature rotating through the angle corresponding to one tooth pitch during a complete cycle of the alternating current applied to the coil 22.

If the invention is applied to a magnetic driving unit for a loud speaking telephone

instrument, the tongue can be replaced by a reed, such as is commonly used in such instruments, which reed may be connected to drive the diaphragm of the instrument; for example, in the case of an instrument with a 5 large diaphragm, by a direct connection.

When the invention is applied to a generating type of instrument such as a magnetic electric machine, the moving member, is, of course, driven, that is to say, either oscillated or rotated, but in either case the flux in the local circuit will be of a fluctuating nature.

I claim:—

1. An electromagnetic device of the class set forth comprising a magnetic structure 15 consisting in the combination of a magnetic circuit of low reluctance containing the effective air gap of the device, a movably-mounted armature included in said magnetic circuit, a coil linked with said magnetic circuit to carry fluctuating electric currents and a magnetic member co-operating with a part of said magnetic circuit to form a circuit for a substantially steady polarizing flux with two paths in parallel and of substantially higher reluctance than said magnetic circuit.

2. An electromagnetic device of the class set forth comprising a magnetic structure 30 consisting in the combination with a pair of pole pieces with polar faces adjacent an effective air gap and a magnetic bridge piece connecting said pole pieces to form a magnetic circuit of low reluctance of a movably-mounted armature located in said air gap, a coil surrounding said bridge piece to carry fluctuating electric currents and a magnetic member co-operating with said pair of pole pieces to form a circuit for a substantially steady polarizing flux with two paths in parallel and of substantially higher reluctance than said magnetic circuit.

3. An electromagnetic device of the class set forth comprising a magnetic structure 45 consisting in the combination of a magnetic circuit of low reluctance containing the effective air gap of the device, a pivotally-mounted armature capable of oscillating movement included in said magnetic circuit, a coil linked with said magnetic circuit to carry fluctuating electric currents and a magnetic member co-operating with a part of said magnetic circuit to form a circuit for a substantially steady polarizing flux with two paths in parallel and of substantially higher reluctance than said magnetic circuit.

4. An electromagnetic device of the class set forth comprising a magnetic structure 60 consisting in the combination of a magnetic circuit of low reluctance containing the effective air gap of the device, a movably-mounted armature included in said magnetic circuit, a coil linked with said magnetic circuit to carry fluctuating electric currents and a magnetic member co-operating with a

part of said magnetic circuit to form a circuit for a substantially steady polarizing flux with two paths in parallel and of substantially higher reluctance than said magnetic circuit, each of said two paths including a 70 permanent magnet producing the steady polarizing flux.

5. An electromagnetic device of the class set forth comprising a magnetic structure 75 consisting in the combination of a magnetic circuit of low reluctance containing the effective air gap of the device, a movably-mounted armature included in said magnetic circuit, a coil linked with said magnetic circuit to carry fluctuating electric currents and a magnetic member embodying two paths in parallel for a steady polarizing flux and of substantially higher reluctance than said magnetic circuit, the magnetic circuit of the steady polarizing flux consisting of said magnetic member and a part of said magnetic circuit of low reluctance not linked with said coil.

6. An electromagnetic device of the class set forth comprising a magnetic structure 80 consisting in the combination of a magnetic circuit of low reluctance containing the effective air gap of the device, a movably-mounted armature included in said magnetic circuit, a coil linked with said magnetic circuit to carry fluctuating electric currents and a magnetic member embodying two magnetic paths in parallel each including a magnet producing a steady polarizing flux which flows also through a part of said magnetic circuit of low reluctance not linked with said coil, said magnetic member having a relatively high reluctance.

7. In an electromagnetic relay, the combination with a pair of pole-pieces with their faces adjacent the effective air gap of the relay, a pivotally mounted armature located in said air gap and a magnetic core connecting said pole-pieces to complete a magnetic circuit of low reluctance, of a coil surrounding said core to carry fluctuating electric currents, and a magnetic member of higher reluctance than said magnetic circuit and embodying two magnetic paths in parallel each including a permanent magnet producing a steady polarizing flux which flows also through said pole-pieces and said armature.

8. An electromagnetic device of the class set forth comprising a magnetic structure 120 consisting in the combination with a pair of pole pieces with polar faces adjacent an effective air gap and a magnetic bridge piece connecting said pole pieces to form a magnetic circuit of low reluctance with a movably-mounted armature located in said air gap, a coil surrounding said bridge piece to carry fluctuating electric currents, a magnetic member co-operating with said pair of pole pieces to form a circuit for a substantially steady polarizing flux with two paths 125 130

in parallel and of substantially higher reluctance than said magnetic circuit and an adjustably-mounted magnetic biassing member co-operating with said pole pieces to balance out the flux linked with said coil when no current is flowing.

9. In an electromagnetic relay, the combination with a pair of pole pieces having faces adjacent the effective air gap of the relay, a pivotally mounted armature located in said air gap and a magnetic core connecting said pole-pieces to complete a magnetic circuit of low reluctance, of a coil surrounding said core to carry fluctuating electric currents, a magnetic member of higher reluctance than said magnetic circuit and embodying two magnetic paths in parallel, each including a permanent magnet producing a steady polarizing flux which flows also

through said pole-pieces and said armature, and an adjustably-mounted magnetic biassing member co-operating with said pole-pieces to balance out the flux linked with said coil when no current is flowing.

20 10. In an electro-magnetic relay, in combination, a magnetic structure formed with pole faces adjacent the effective air gap of the relay, a vibratory armature located in said air gap, a coil mounted on said magnetic structure to carry fluctuating electric currents, and a biassing member adjustable during the operation of the relay, independently of the adjustment of any other parts.

25 11. In an electro-magnetic relay, comprising in combination, a magnetic structure formed with pole faces adjacent the effective air gap of the relay, a vibratory armature located in said air gap, a coil mounted on said magnetic structure to carry fluctuating electric currents, and a movable magnetic member adjustable for biassing the relay during operation of the latter while the position of said abutments relatively to said tongue remains fixed.

30 40 45 12. In an electromagnetic relay, in combination, a magnetic structure formed with pole pieces adjacent the effective air gap of the relay, a vibratory armature mounted to co-operate with said pole pieces, a coil supported on said magnetic structure to carry fluctuating electric currents, and a magnet mounted for adjustment during the operation of the relay so as to set the bias of the relay independently of the adjustment of any other parts.

50 55 60 65 13. In an electromagnetic device of the class set forth, the combination of a magnetic structure having a pair of opposing pole pieces with an air gap between them, a vibratory armature mounted to vibrate under the forces of attraction of said pole piece, a coil supported on said magnetic structure to carry fluctuating electric currents and a movably mounted member for adjusting the forces of attraction of said pole pieces on said

armature independently of the adjustment of other parts.

14. In an electromagnetic device of the class set forth, the combination of a magnetic structure having a pair of opposing pole pieces with an air gap between them, a vibratory armature mounted to vibrate to and from said pole piece, a coil supported on said magnetic structure to carry fluctuating electric currents and a magnetic member movably mounted for adjustment during the operation of the device in order to set the position of said armature relatively to said pole piece independently of the adjustment of any other parts.

70 75 80 In witness whereof I hereunto subscribe my name this 26th day of March, 1929.

RUPERT EVAN HOWARD CARPENTER.
